DOOR LOCKING MECHANISM FOR FREIGHT CONTAINERS

Benjamin F. Fitch, Greenwich, Conn., assignor to Motor Terminals Company, New York, N. Y., a corporation of Delaware

Application January 6, 1934, Serial No. 705,529

10 Claims. (Cl. 189—46)

A system of handling package freight by means of demountable bodies which may be carried on highway trucks and lifted intact with their loads to railway cars for intermediate rail transportation, and thereafter transferred at the distant end to trucks for ultimate delivery, has many advantages, reducing the cost of shipping from consignor to consignee, reducing the time involved, and reducing the loss due to pilferage or 10 breakage.

In a system of this kind it is important that the container doors make a close connection with the door jams to prevent access of water or snow to the interior of the body. As the door openings 15 should be as wide as practicable to allow convenient loading and unloading, two doors for each opening, each hinged to the body at the outer edge constitute the preferable means for closing the opening. Such double doors should be effectively closed at their meeting edges, and as 20 there may be considerable impact of the contents against the doors, particularly the end doors, during transit, it is important that the doors be braced against outward distortion.

It is a primary object of the present invention to provide means whereby a hinged door, while adapted to swing freely whenever desired, may make a tight connection with the door jamb when the door is closed. I effect this by mechanism to 25 raise the door at the hinged edge thereof after it has swung into the region of the jamb, and I so arrange the top and bottom of the door and the cooperating portions of the jamb that when the door is thus raised it will make a tight connection both at the top and bottom. Moreover, I provide a removable upright post or bar overlapping the free edges of the closed doors, to close the gap and effectively brace the doors, and I form the lower portion of such brace bar with 30 an inward projection which is adapted to extend under the doors at their meeting edges and prevent the doors sagging or being lowered.

It results from the door raising mechanism at the hinge and the brace at the opposite edge of 45 the door, that the door when raised is effectively supported at its two side edges. It results further that the brace may not be applied until the doors are not only shut but raised, and hence, there is no danger of inadvertently shipping the container 50 without the doors being tightly raised, since the last act of closing the container is to apply the brace bar to the doors and secure it in place.

While my means for locking the door acts to 55 support it adjacent each edge, so there is no tendency to sag or institute strains in the door

or on the door jamb, nevertheless if the raising mechanism at the hinged edge should be inadvertently operated into lowering position when the brace bar is in place, the projection of the brace bar beneath the free edge of the door will 5 maintain the door in its elevated position.

My invention is hereinafter more fully described in connection with an illustrative embodiment shown in the drawings, and the essential novel features are set out in the claims. 10

In the drawings Fig. 1 is a side elevation of a demountable body having side doors embodying the present invention; Fig. 2 is an end view of such body showing end doors embodying the invention; Fig. 3 is an enlarged fragmentary elevation intermediately broken away, of the construction at the hinges of either the side or end door; Fig. 4 is a vertical section through one of the doors when tightly closed, as indicated, for instance, by the section-line 4—4 on Fig. 3; Fig. 5 15 is a similar vertical section showing the door when shut but before it has been raised into tightly closed position, being a vertical section along the line 5—5 in Fig. 6; Fig. 6 is an elevation similar to Fig. 3 but showing the door in its lowered, though unopened, position; Fig. 7 is a horizontal section through a pair of coating doors and one of the supporting portions of the body 20 adjacent the hinge, as indicated by the line 7—7 on Fig. 1; Fig. 8 is a view similar to Fig. 7 but 25 showing the brace bar detached and the doors partially open; Fig. 9 is a vertical section through one of the doors adjacent its free edge and looking toward the side of the applied brace bar; Fig. 10 is a similar view showing such parts with the 30 brace bar being removed and the door lowered; Fig. 11 is a detail of the brace bar bolts, as indicated by the line 11—11 on Fig. 10. 35

In Figs. 1 and 2, I have shown a demountable body having a floor frame 10, side walls 11, narrow end walls 12, and a roof 13. Each side is provided with a pair of lift hooks 14, extending above the eaves and suitably braced by extension straps and inclined braces secured to the body 40 sides, as indicated at 15. 45

Each side of the body is provided with a central doorway between the region of the lift members, adapted to be closed by a pair of hinged doors 20. Likewise, each end is provided with a doorway which is only slightly smaller than the 50 transverse internal dimension of the container, and this doorway has a similar pair of hinged doors 20.

The floor frame 10 of the body comprises end and longitudinal sills and suitable internal brac- 55

ing. An end sill is shown in Figs. 4 and 5 in the form of a channel 30. A lower layer of flooring 31 rests on this end sill. The bottom member of the door jamb in the form of a Z-bar 40 is 5 secured to the channel 30 and extends across the edge of the planking layer 31, and then inwardly at 41 on top of that layer, then upwardly at 42 along the edge of a surmounting layer of planking 32. The extreme edge of this door jamb 10 member is bent downwardly as shown at 43, for a purpose hereinafter described.

Over the end doorway is a metal sheet 16, which forms a portion of the end wall, lying in the same plane with the narrow vertical portions 12. This 15 top end wall near its lower edge carries the upper door jamb, which is shown as a bent piece of metal embracing the lower edge of the sheet 16 and providing a downwardly facing door seat. This bent piece has a portion 50 on the outer side of the 20 plate 16 and is then doubled back on itself around the lower end of the plate 16 to provide a portion 51 bearing against the inner face of the plate 16. Then there is a horizontally extending portion 25 52, and finally a downwardly extending flange 53. This inwardly extending portion of the jamb is shown as braced by an angle bar 55, engaging the inner surface of the sheet 16 and the top of the jamb portion 52. On the outer side of the body 30 in this locality is a reinforcing member 57 in the form of a horizontal Z-bar having a downward flange 58 and an upward flange 59. The parts described are all riveted together and constitute a very stiff brace for the lower end of the end wall 16, extending from side to side of the body above 35 the wide door opening.

The end walls 12 of the body heretofore referred to comprise outer sheets which are connected to the sides 11 by vertical corner angle bars 18. The end sheets 12 are also braced by inner sheets 60, 40 Figs. 7 and 8, which at their outer ends are secured to the body sides 11 and near their inner ends bend inwardly at 62 and are finally flanged at 63 into the plane of the sheet 12. Then I add a sheet 65, which is riveted to the outer side of the 45 sheet 12 at its inner edge, and passes over the flange 63, and is then doubled back onto the rear face of that flange and finally lies alongside of the portion 62 of the plate 60, as shown at 66. This additional plate 65 and plate 60 are preferably welded or otherwise secured together.

It will be seen that the construction just described makes a firm vertical end wall for the body at either side of the door opening, and likewise, by reason of the flange 63 and the doubled over portion 65, provides a door jamb having a lip 55 extending across the door opening. The hinge axis of the door is beyond the plane of the door and in front of this lip so that the door when closed is adapted to seat in the recess behind the 60 lip. It will be observed that the complete door jamb provides one form of seat at the two vertical sides of the doorway, a different form of seat at the bottom, and a still different form at the top. The door is so formed and mounted that it may 65 coact with these special seats as about to be described.

Each door panel 20 is bounded at its extreme edge by a reinforcing member 70 in the form of a channel embracing the edge of the door. This 70 reinforcing member has a flange 71 projecting from it at right angles to the door. When the door is closed, the face 72 of the reinforcing member 65, while the projecting flange 71 comes into

contact with the rounded portion of the member 65, where it is doubled on itself.

The construction described makes a tight connection at the hinged vertical edge of the door when the same is shut. There is, however, clearance at the top and bottom of the door. The door-raising mechanism of this invention may now come into play to raise the door and effect a tight connection at the top and bottom, as follows:

The hinges proper comprise a bracket 80 having a vertical socket 81 secured to the door jamb, and bracket 82 secured to the door panel and having a downwardly extending pin 83 loosely occupying the socket. These features are the only characteristics of the upper and lower hinges, but 15 at the middle hinge, loosely surrounding the pin between the socket and the bracket where it engages the pin is a lever 85, which has its under-surface formed into an arcuate crown cam 86, adapted to coact with an oppositely directed 20 crown cam surface 87 on the socket member of the hinge.

When the door is in its lowered position, as indicated in Fig. 6, the complementary surfaces of the hinge socket and lever nest together and the lever arm extends alongside of the body wall and the door is free to swing, its middle bracket 82 having its under horizontal surface at the top of the exposed pin sliding circumferentially on the horizontal top surface of the lever. Now when the door has been shut into the jamb, if the lever is then given a movement of substantially 180°, its cam 86 acts on the cam 87 of the hinge socket to raise the lever and door into the position illustrated in Fig. 3. In this position the lever comes 25 beneath the cross web 88 of the door bracket and may be locked thereto by a pin 89 passing through registering openings in the web and lever, as indicated in Fig. 3.

On the outer face of the door near the top is 40 secured a horizontal rod 90, which forms a bead or molding. Along the bottom of the door is a flat strip 91, which projects inwardly from the door and then is bent diagonally upwardly. When the door is shut and raised as shown in Fig. 3, 45 the bead 90 makes a snug engagement with the doubled over edge of the top reinforcing member 50, while the inclined projection of the plate 91 makes a substantially close connection with the down-turned flange 43 of the base door jamb. 50 Accordingly, access of water is prevented either at the top or bottom of the door. As the same time the side edges of the door are behind the vertical lips 65 with the vertical flange 71 engaging 55 the edge of such lip.

It will be apparent from the description before given that when either door is closed it makes a tight connection with the jamb at the top and bottom and hinged edge. To prevent access of water at the free meeting edges of the doors, as 60 well as to brace and support them and insure their being locked, I provide a locking post overlapping the two doors and engaging keepers at its upper and lower end, as indicated in Figs. 7 and 8.

Briefly, the locking post may be made of a pair 65 of main angle bars 100 secured together back to back, and a pair of supplemental angle bars 101, secured to the outer faces of inwardly extending portions of the angle bars 100. Mounted in the recesses provided by the parallel freely projecting flanges of the angle bars 100 and 101 are bolts 105, which are retained in place by vertical angle plates 106. The upper ends of the bolts are bent outwardly to form handles, as illustrated. Near its upper end, the locking post has a pair 75

of projecting tongues 108. When the post is in place, these tongues project behind the body flange 58 and the bolts 105 may extend downwardly into a keeper 109, secured to the floor-frame. A seal wire passed through one of the handles and one of the post flanges prevents sur-ruptitious raising of a lowered bolt.

The free edge of the door is embraced by a channel-shaped boundary member 74, similar to the member 70, heretofore described, and having a flange 75 projecting on the outer face of the door. When the doors are closed, as shown in Fig. 7, the inward flanges of the post 100 extend between the doors, while the lateral flanges 101 seat against the two boundary members 74 between the flanges 75 thereof, and thus a weather-tight connection is made over the meeting edges of the doors.

It will be seen from Figs. 9 and 10 that the locking post is provided with a projection 110 on its inner face adjacent the bottom, which has an inclined top, this projection being made by the web of the bar and top flanges which may be a continuation of the inner flanges 101 of the post. Now these wedge projections extend under the doors adjacent their free edge and effectively support such edges so that the door cannot sag or lose its tight connection with the jamb either at the top or bottom.

The locking post not only makes an effective batten strip for the doors, resulting in a weather-tight connection at the meeting edges; an effective brace, preventing outward bulging, and an effective support for the doors at free edges, but it insures the doors being elevated into snug position before the container is shipped. That is to say, on account of the projection 110 the post cannot be put in place until the doors are elevated by the hinge levers, and hence the possibility of shipping the container with the doors lowered is overcome, as the last act in dispatching the container is to position the locking post and bolt it in place and apply the bolt seal.

I claim:

1. In a container having a doorway, and a door hinged to the container in a manner to enable it to have a sliding movement along the hinge axis, the combination of leverage mechanism adapted to be operated from the exterior of the door to raise the door from a normal lower position into an elevated position when it is closed, and a bead on the outer side of the door near the top adapted to come into engagement with a portion of the container when the door is closed.

2. In a container having a door hinged to close an opening therein, and having pin and socket coupled hinge brackets supporting the door, one of the brackets having a cammed or inclined surface, the combination of a lever pivoted on the pin and having a cammed or inclined surface adapted to coact with the said bracket surface in the closed position of the door to vertically move the door and effect a tight joint at one horizontal edge of the door, said lever and one of the brackets having mutually superposed parts and apertures therein which register when the lever has been operated to vertically shift the door, whereby the lever and bracket may be pinned or sealed together in said position of the lever.

3. The combination of a container, a door hinged thereto and slidable along the hinge axis, means for raising the door when closed, a brace bar adapted to act on the free edge of the door to hold it closed, said brace bar having a pro-

jection adapted to extend under the free edge and support the door at that edge.

4. The combination of a container, a door therefor, hinge mechanism connecting the door and container and comprising a socket on one of them and a pin freely occupying the socket on the other, and a lever embracing the pin and having a cam engagement with the hinge, so that the operation of the lever may raise the door, and a brace bar adapted to brace the free edge 10 of the door and having a projection to extend beneath it and support the free edge of the door, thus relieving the strain on said camming lever.

5. The combination of a container having a doorway, a pair of doors hinged to the container 15 adjacent the opposite side edge of the doorway, said doors being adapted to move vertically when closed to make a tight connection at the top of the door, and a removable locking post adapted to extend vertically across the free edges of the 20 two doors to make a tight connection in that region, said post having projections engaged beneath the raised doors adjacent their free edges to prevent the lowering of the doors so long as the post is in place.

6. The combination of a container having a doorway with a projecting flange at the vertical edges, a pair of doors hinged to the container in such manner that when the doors are closed the hinged edges will project behind said flanges 30 and make a snug connection therewith, said doors being hinged in such manner that they are capable of vertical movement, means for moving the doors vertically when closed to effect a tight connection at the top and bottom, and a removable 35 locking post adapted to overlap the free edges of the two doors and make a tight connection in that region, whereby the connection is tight for the entire boundary of the two doors, said post having projections engaged beneath the raised 40 doors adjacent their free edges to prevent the lowering of the doors so long as the post is in place.

7. The combination of a container, a door hinged thereto by slideable hinges, mechanism 45 adapted to raise a closed door to make a tight connection, a vertical brace bar for the door having a projection at its lower end adapted to extend beneath the door, said projection having an inclined top whereby it may act to slightly raise 50 the door to insure a tight engagement when the projection is inserted beneath it and thus relieve the supporting strain on said raising mechanism.

8. The combination of a container having a doorway, a pair of doors hinged to opposite sides 55 of the doorway by slideable hinges, a vertical locking post adapted to overlap the meeting edges of the doors, keepers for the post at the top and bottom of the doorway, a bolt for locking the post, inward projections on the post adapted to extend beneath the raised doors, cam mechanism at the respective hinge axes of the doors for raising the doors when closed, and means on the top and bottom of the doors for making a tight connection of the container when the doors are 60 raised.

9. In a demountable body having a door hinged thereto by hinges capable of sliding along their axis while remaining engaged, the combination of means for moving the door in its own plane 70 when closed, and a brace bar for the door having a projection adapted to enter the space resulting from such movement of the door, whereby the reverse action of the moving mechanism will not 75 of itself free the door.

10. In a freight container having a doorway, and a door hinged to the container in a manner to enable it to have a certain vertical movement, when closed, the combination of leverage mechanism adapted to raise the door, a projecting plate at the bottom of the door having an upwardly di-

rected inner edge, and a downwardly projecting flange on the floor of the container below the top surface of the floor, said plate being positioned to underhang the flange when the door is raised.
